UNITED STATES PATENT OFFICE.

GEORGE A. ARNOLD, OF BOSTON, MASSACHUSETTS, ASSIGNOR TO JAMES A. ABELES.

VACUUM-TANK FOR FUEL-FEED SYSTEMS.

1,299,653.

Specification of Letters Patent.

Patented Apr. 8, 1919.

Application filed November 1, 1917. Serial No. 199,748.

To all whom it may concern:

Be it known that I, GEORGE A. ARNOLD, a citizen of the United States, and resident of Boston, in the county of Suffolk and State 5 of Massachusetts, have invented certain new and useful Improvements in Vacuum-Tanks for Fuel-Feed Systems, of which the following is a specification.

In my prior application, Serial No. 189,287, 10 Sept. 1, 1917, I have disclosed a gasoline register adapted to be operated by the intermittently formed vacuum in the fuel feed tank of certain types of liquid feeding systems for internal combustion engines. My 15 present invention relates particularly to the construction of mechanism within the tank and has for its object to insure the accurate dumping of predetermined quantities of the liquid fuel within the tank.

20 In the tanks to which my present invention is particularly applicable, there are formed two compartments or chambers through which the gasoline or other liquid fuel passes in succession. One of these is 25 provided with a float and valve mechanism whereby this chamber may be connected to the intake manifold or other source of partial vacuum and at the same time connected to the main fuel tank so that the partial 30 vacuum in the compartment will draw up gasoline from the supply tank. The raising of the float to a predetermined position operates to reverse the valve mechanism, close the vacuum communication and open an air 35 vent so that the in-flow of gasoline will stop and the gasoline may flow by gravity to the other or lower compartment and from which it may flow to the carbureter.

40 In the constructions now commonly employed, the reversing of the valve mechanism is accomplished by means of one or more springs thrown past dead center by the float. Due to variations in the character or tension of these springs, different tanks, al- 45 though apparently of the same construction, will operate to reverse the valve mechanism and dump different quantities of the liquid after different quantities have passed from the upper to the lower compartment, the 50 quantity passing between successive rever- sals of the valve mechanism varying with the character of the controlling springs. In my improved construction, I provide means whereby the necessity for these springs is

avoided and the reversing of the valve mechanism is positively controlled so that there will be greater accuracy in the operation, and uniformity of volume of the successively dumped mass will be secured. 55

In the accompanying drawing, I have 60 illustrated one embodiment of my invention, the said drawing showing a central vertical section through the device.

I have illustrated my invention as being 65 embodied in a liquid fuel feeding apparatus of the character illustrated in the Jay Patent No. 1,125,549, but I do not wish to be in any way limited to the specific features of construction which are here shown the same as in the Jay patent and which form no part 70 of my invention.

I have shown merely the auxiliary tank having an outer casing 10 and an inner casing 11 united at their upper ends and closed by a cover 12. The inner casing 11 has its 75 peripheral wall spaced from the peripheral wall of the outer casing and its bottom spaced above the bottom of the outer casing so as to form two compartments 13 and 14. These communicate through a check valve 80 controlled passage 15 in the bottom of the inner and outer compartment. The cover has a gasoline supply pipe 16, a vacuum pipe 17 adapted to be connected to the intake manifold or other source of low pressure and a vent pipe 18, one end of which may open to the atmosphere. The cover is also shown as having a passage 19 whereby the outer or lower compartment 14 may at all times communicate with the atmosphere. 85 90

At the inner ends of the vacuum and vent pipes are valve seats 20 and 21 and coöperating with these seats are valves 22 and 23. The valve 22 which controls the vacuum 95 pipe moves inwardly from its seat while the valve 23 which controls the vent moves outwardly from its seat. The valve stems of the two valves are connected to a lever 24 pivoted on a stud or lug 25 which may be 100 cast integral with the cover. The parts so far described may be substantially identical with those shown in the Jay patent or may be constructed in any other manner common in the art as they form no portion of my 105 present invention.

Within the inner compartment, there is a float 26 mounted to slide on a tube 27 which

latter may be rigidly supported in any suitable manner. I have shown the lug 25 as having a depending arm 28 attached to one side thereof and with its lower end bent at right angles and rigidly connected to the upper end of the tube 27. Within the tube 27 is a vertically movable rod 29 having a pair of pins 30 and 31 projecting outward radially therefrom. The lower pin 30 is below the lower end of the tube 27 while the upper pin 31 extends out through a slot 32 in the wall of the tube. These two pins are positioned below and above the float respectively and are spaced apart a sufficient distance to permit the desired movement of the float independently of the rod. The upper end of the rod is connected by an arm 33 to one end of the lever 24 so that as the rod is raised or lowered by the float, the lever 24 may be swung to operate the valve mechanism.

To positively insure the locking of the valve mechanism in a predetermined position until after the float has moved to its given position, and to thereby insure the operation of the valve mechanism after exact and predetermined quantities of liquid have accumulated in the upper compartment, I provide the lever 24 with an extension 34 carrying a roller 35 at its outer or free end. The cover 12 has a depending lug 36 carrying a stop 37 in the path of the roller 35. This stop is shown as a pin having a hemispherical end and slideable in a tubular guide 38 and normally held in operative position by a very light spring 39. A further very light spring 40 may encircle the valve rod of the valve 22 and normally press it lightly toward its seat.

40 The operation of my improved device is substantially as follows:

With the parts in the position indicated in the drawing, the vent valve 23 is closed and the vacuum valve 22 is open. If the engine be running, the resulting lowering of the pressure in the compartment 13 will cause gasoline to flow up from the main tank through the pipe 16 and slowly fill the compartment 13. As the float rises, it engages the pin 31 and further movement raises the rod 29, arm 33 and lever 24. The continual supply of liquid raises the float and moves the parts operated thereby until the roller 35 passes the rounded end of the stop 37. At this instant, the predetermined amount of liquid has been received and the pressure of the spring 39 swings the lever past the dead center position and suddenly closes the vacuum valve 22 and opens the vent valve 23. This destroys the vacuum and stops the in-flow of liquid. The parts will remain in this position until a sufficient amount of liquid has flowed from or been dumped from the upper compartment into the lower and the lowering of the float has pulled down to

a sufficient extent on the rod 29 and the attached parts. During this lowering movement the spring 40 will hold the vacuum valve to its seat until the roller 35 again passes the center of the rounded end 37 of the stop and the pressure of the stop forces the lever to the final or limiting position shown in the drawing, and the valve mechanism is reversed to again begin the in-flow of liquid.

75 By means of my improved valve controlling mechanism, I insure a more positive and accurate movement of the valve mechanism and enable the device to constitute an accurate and effective measure for the liquid fuel delivered to the engine. By knowing the exact amount which flows into the upper compartment and which is necessary to raise the float and stop the in-flow, the vacuum tank may serve to operate a register of the 85 character shown in my application above referred to, and permit the latter to register with great accuracy the amount of gasoline supplied to the engine.

As an important feature of my improved 90 construction, I provide means whereby the volume dumped may be adjusted and each tank brought to a uniform standard. As a means of adjustment, I have shown the upper pin 31 provided with an adjusting screw 95 47 normally held by a lock nut. The float in rising strikes the lower end of this adjusting screw and through it raises the rod. The adjustment of the screw permits of a variation of the amount of lost motion and 100 this largely, if not wholly, determines the volume dumped.

Having thus described my invention, what I claim as new and desire to secure by Letters Patent is:

105

1. An auxiliary fuel tank for vacuum feed systems, including upper and lower compartments, the upper compartment having a fuel supply pipe and the lower compartment having a fuel delivery pipe, a float 110 within the upper compartment, valve mechanism operated by said float for alternately establishing communication between said upper compartment and the atmosphere and the source of vacuum, a lever operated by 115 said float for controlling said valve mechanism, and a spring pressed stop in the path of said lever and movable out of said path by the engagement of the lever therewith during the swinging of the latter and serving to hold the lever in either of two limiting positions.

2. An auxiliary fuel tank for vacuum feed systems, including upper and lower compartments, the upper compartment having a 125 fuel supply pipe and the lower compartment having a fuel delivery pipe, a float within the upper compartment, a valve mechanism operated by said float for alternately establishing communication between 130

- said upper compartment and the atmosphere and the source of vacuum, a lever operated by said float for controlling said valve mechanism, and a stop in the path of said lever 5 and serving to hold the lever in either of two limiting positions, said lever having a roller carried thereby and said stop being spring pressed and movable into or out of the path of movement of said roller.
- 10 3. An auxiliary fuel tank for vacuum feed systems, including an upper compartment having a cover provided with a liquid fuel inlet, a vacuum gas outlet and an air vent, a lug depending from said cover, a lever 15 pivoted on said lug, an inwardly opening valve for said gas outlet and connected to said lever, an outwardly opening valve for said air vent and connected to said lever, a spring pressed stop in the path of movement of said lever and operating to hold 20 the same in either of two limiting positions, and a float connected to and serving to operate said lever.
4. An auxiliary tank for vacuum feed systems, including a tank having valve mechanism for controlling the communication between said tank and a source of vacuum or the atmosphere, a pivoted lever connected to said valve mechanism, a rigid sleeve within 25 said tank, a rod within said sleeve, a float mounted to move on said sleeve and having 30 lost motion connections with said rod, and an arm connecting said rod and said lever.
5. In an apparatus of the character described, a tank, a liquid fuel pipe leading 35 into the same, a vent pipe leading into said tank, an exhaust pipe leading into said tank, valve mechanism coöperating with the exhaust and vent pipes for controlling the latter, a float, connections between said float 40 and said mechanism and including a pivoted lever, and a spring pressed stop in the path of movement of said lever and movable out of said path by the swinging of said lever and normally tending to hold said lever in 45 one of two limiting positions.
6. An auxiliary fuel tank for vacuum feed systems having an air vent, and vacuum connections, valve mechanism for controlling the same, a rigid sleeve within said tank, a 50 rod within said sleeve and having a pair of spaced radially extending projections, connections between said rod and said valve mechanism, a float mounted to move on said sleeve between said projections, and means 55 carried by one of said projections for varying the extent of relative movement of the rod and float.

Signed at New York, in the county of New York and State of New York, this 31st day 60 of October, A. D. 1917.

GEORGE A. ARNOLD.
